UNITED STATES PATENT OFFICE.

WILLIAM E. FOWLER, JR., OF MOUNT LEBANON, PENNSYLVANIA, ASSIGNOR TO DAVIS BRAKE BEAM COMPANY, OF JOHNSTOWN, PENNSYLVANIA, A CORPORATION OF PENNSYLVANIA.

SHOE FOR BRAKE-BEAM SUPPORTS.

Application filed May 15, 1924. Serial No. 712,558.

To all whom it may concern:

Be it known that I, WILLIAM E. FOWLER, Jr., residing at Mount Lebanon, in the county of Allegheny and State of Pennsylvania, 5 a citizen of the United States, have invented or discovered certain new and useful Improvements in Shoes for Brake-Beam Supports, of which improvements the following is specification.

10 The invention described herein relates to certain improvements in what is known as three-points supports from the brake beams of four wheeled trucks and especially to that type of support consisting of a shoe, 15 or as it is sometimes termed, a carrier, connected to the strut and movable along inclined end portions of a supporting rail so secured to the spring plank of the truck that the upwardly inclined end portions of 20 the rail will be in line vertically with the strut of the brake beam. The improvement is hereinafter more fully described and claimed.

In the accompanying drawings forming 25 a part of this specification, Fig. 1 is a top plan view of a portion of the spring plank, a truss brake beam and a supporting means for the latter, embodying the improvement claimed herein; Figs. 2, 3 and 4 show the 30 improved shoe in plan, front, and side elevations on an enlarged scale; Fig. 5 is a side elevation showing the position of the form of shoe shown in Fig. 2 to 4 relative 35 to the supporting rail and tension member; and Fig. 6 is a view similar to Fig. 5 and illustrating a modification of the shoe.

In the practice of the invention the improvement consists of a body portion 1 having a slot 2 for the reception of the supporting rail. On this base or body portion 40 are formed open-topped seats or saddles 3 for the reception of the tension member 4 of the brake beam. These saddles are spaced a distance apart at least equal to the 45 width of the strut 5 in line with the tension member so that the saddles will form seats for the reception of the tension member on opposite sides of the strut. These saddles which consist of spaced fingers 6, are op-

positely inclined at angles corresponding to 50 the angles of the tension member to the strut.

The shoe may be so constructed that the fingers will be at right angles to the rail when the shoe is placed thereon, as shown in Figs. 1 to 5, or it may be constructed as 55 shown in Fig. 6 so that when the tension member rests in the saddle the shoe will be directly under the tension member. The length of the fingers, or depth, in the form shown in Fig. 6, need not be materially 60 greater than the diameter or thickness of the tension member, but when the shoe is constructed as shown in Figs. 2 to 5, the fingers should be made longer so as to ensure the engagement of the inner finger or 65 those lying inside of the tension member with the latter.

It is characteristic of the improvement described and claimed herein that the improvement can be used in connection with practically any construction of truss brake beam and that as the saddles engage only the tension member, reconstruction of the strut is not necessary. And further, in case of 70 repairs either the brake beam or supporting 75 members can be removed and replaced without interference one with the other; the seats or saddles being open topped. The weight of the brake beam maintains the operative 80 relation between the tension member and the shoe.

I claim herein as my invention:

1. A shoe for brake beam supports consisting of a base or body portion slotted for the reception of a supporting rail and provided with spaced open-topped seats for the 85 reception of the tension member of the brake beam.

2. A shoe for brake beam supports consisting of a base or body portion slotted for the reception of a supporting rail and provided with spaced and oppositely inclined 90 seats for engagement with the tension member of a brake beam on opposite sides of the strut. 95

In testimony whereof, I have hereunto set my hand.

WILLIAM E. FOWLER, JR.
